CLOSURE DEVICE FOR TUBES AND OTHER CONTAINERS

Karl Ruetz, Zurich, Switzerland

Application December 12, 1936, Serial No. 115,625
In Switzerland December 17, 1935

2 Claims. (Cl. 221—60)

The present invention relates to a sliding closure device for tubes and other containers, such device being characterized in that between the outlet aperture of the container and the slide 5 to be actuated there is arranged a wedge member, the lower side of which is provided with a packing plate and which participates in the movement of the slide over at least a part of its path, in such manner that on the opening movement of the slide the wedge pressure on the edge of the opening is first of all removed, and then the wedge member with the packing plate is displaced by the slide for the purpose of exposing the opening in order that the packing plate may be protected against damage and undue wear.

The annexed drawing illustrates diagrammatically one form of construction of the invention.

Fig. 1 is a vertical section with the slide closed.
20 Fig. 2 is a vertical section with the slide open.
Fig. 3 is a section along the line A—B of Fig. 1.
Fig. 4 is a plan of the slide.

From the surface 1 of a cylindrical tube 2 rises a nozzle 3 having an opening 4 for the evacuation of the contents of the tube. On the polished surface 5 of the nozzle 3 of the tube there is disposed, so as to be displaceable in the same direction as a slide 11, a packing plate 6 formed, for instance, of cork which is fixed on the inner side of a wedge member 7. The latter has lateral downwardly-projecting flanges 8 which engage loosely in gaps 9 between the nozzle 3 and the side flanges 10 of the slide 11. The side flanges 10 are guided with inwardly bent guide bars 12 between the surface 1 of the tube 2 and ribs 13 provided on both sides of the nozzle 3. The wedge member 7 is provided with an upwardly directed projection 14 which engages with lateral friction in a recess 18 in the slide 11. At the front of the slide 11, under the recess 18, is a conical surface 19 which is inclined in the same manner as the oppositely inclined surface of the wedge member 7, and at the rear end has a gripping bar 20 for facilitating the actuation of the slide.

When the slide is in the closed position, as

shown in Fig. 1, the packing plate 6 is pressed by the wedge member 7 firmly against the edge of the opening 4. If the slide 11 is thrust into the position shown in Fig. 2, that is to say in the open position, then after the initial idle movement it carries with it the projection 14 and therefore the wedge member 7 until the flanges 8 of the wedge member are held firmly on the vertical end walls of the gaps 9. At the beginning of the opening movement of the slide 11, before the wedge member 7 is displaced, the slide is displaced in relation to the wedge member 7 so that the wedge connection between the two parts ceases, and therefore the pressure of the packing plate 6 on the polished surface 5 or 15 the edges of the opening of the tube is reduced, and not until then does the displacement of the packing plate take place in the same direction as the movement of the slide.

The slide 11 may be made of metal or of artificial material.

Having thus described the nature of the said invention and the best means I know of carrying the same into practical effect, I claim:—

1. A sliding closure device for tubes and other containers embodying a slide to be actuated, characterized in that between the outlet opening of the container and the slide there is arranged a wedge member provided on its lower side with a packing plate, which wedge member participates in the movement of the slide over at least a part of its path, in such manner that on the initial movement of the slide, the wedge pressure on the edge of the opening is first of all removed, and then the wedge member with the packing plate 25 is displaced by the slide for the purpose of exposing the opening in order that the packing plate may be protected against damage and undue wear.

2. A sliding closure device according to claim 40 1, characterized in that the container carrying the closure device has a nozzle which is provided with lateral ribs and the wedge member engages by means of a projection in the slide which is guided by said lateral ribs.

KARL RUETZ.
